(57) **CLAIM**

The ornamental design for a silicone therapy belt, as shown and described.

DESCRIPTION

FIG. 1 is a first perspective view of a silicone therapy belt showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is a partial view of FIG. 1; and,

FIG. 10 is another perspective view in alternate state of use. The dot-dash broken line(s) define the bounds of the claimed design and form no part thereof.

The broken lines in FIG. 10 illustrate environment and forms no part of the claimed design.
